RESILIENT INSOLE

Meyer Margolin, Elgin, Ill.

Application May 8, 1939, Serial No. 272,364

8 Claims. (Cl. 36—3)

My invention relates to a novel resilient insole and more particularly to an insole, the forepart of which is resilient with a periphery of material stiff enough to hold the necessary stitching for attachment of the insole in the shoe. My novel insole has grooves located on the bottom thereof, which grooves are substantially rectangular in cross section. The grooves are adapted to be compressed and expanded to provide forced breathing which is transmitted by suitable perforations in the insole to the interior of the shoe.

I provide ball cushion support for the foot by means of a central resilient portion of greater thickness than the edge portion of lap and insole.

The prior art has long recognized the problem of a need for a resilient forepart for the shoe. The desirability of an effective ventilation or forced breathing for the shoe has long been noted, but up to the present time no constructions have been devised which suitably meet the problems of providing resilience and forced breathing in the forepart of the shoe.

My invention comprises a resilient insole, the forepart of which is primarily constructed of materials, such as cellular rubber or other resilient material, and the periphery of which comprises either leather alone or leather in combination with the resilient material, the leather providing stiffening and backing for holding the stitching. The relatively stiff material may be any material, the physical properties of which correspond to leather in this art.

I provide perforations in the resilient material which extend through the resilient material and I also provide certain transverse grooves which are alternately compressed and expanded by the action of the foot in walking so as to force air from these transverse grooves through the perforations to the foot itself.

I provide various constructions by means of which I can achieve the desirable objective of a resilient insole with stiff periphery, which insole is permeable to air and which insole may carry integral therewith metatarsal support and arch support.

My resilient insole is not to be confused with the rubber resilient fillers which have been disclosed in this art. Such fillers lie between the insole and the outsole and although they are resilient in themselves do not increase the resilience of the forepart of the shoe but act only to possibly soften such forepart to the step. Such rubber fillers have been employed to force

air into the shoe only by means of a complex arrangement in which an opening under the main arch is employed. My construction provides for the first time a novel resilient insole which in itself is formed to provide resilience for the forepart of the insole and at the same time a forced breathing simultaneously over a large area of the forepart of the shoe.

It is, therefore, an object of my invention to provide a resilient insert with a periphery sufficiently stiff to hold the necessary stitching.

It is a further object of my invention to provide a resilient insole having transverse grooves extending part way across an insole and perforations adjacent said grooves, said grooves being adapted upon expansion and compression to force air through said perforations.

It is still a further object of my invention to provide a resilient insert in an insole, which insert carries the above described forced breathing grooves and adjacent perforations.

It is a further object of my invention to provide a resilient insole having about its periphery recesses into which are inserted stiffening pieces comprising a stiff toe member, stiff side members, and a stiff shank portion of an insole, in separate sections.

These and further objects of my present invention will become apparent from the description which follows taken in connection with the drawings, in which:

Figure 1 shows a shoe in partial side elevation and partial section, the section showing the general construction of my resilient insert in its normal position.

Figure 2 is a cross-section of an enlargement of my resilient insole in which in descending the foot acts to compress the air contained in the expanded grooves forcing such air out through the adjacent perforations on to the foot.

Figure 3 is a plan view of the bottom of the resilient insole of my invention.

Figure 4 is a cross section taken along the line 4—4 of Figure 3.

Figure 5 is a section taken along the line 5—5 of Figure 3.

Figure 6 is a section of Figure 5 in its bent condition when due to the action of the foot in walking the grooves contained therein are expanded preparatory to being compressed to expel air through the adjacent perforations.

Figure 7 is a plan view of the top of the resilient insole of my invention showing a construction in which the rubber middle portion has a double flap into which double flap are positioned

stiffening members which are adapted to hold the stitching of the shoe.

Figure 8 is a section taken along the lines 8-8 of Figure 7.

Figure 9 is a section taken along the line 9-9 of Figure 7.

Figure 10 is a section taken along the line 10-10 of Figure 7.

Figure 11 is a plan view of the top of a modified form of the resilient insole of my invention in which the rubber middle portion has a single flap and the various stiffening members, comprising a toe stiffening section, side stiffening sections and the shank portion, are laid on to that flap to be united thereto.

Figure 12 is a cross section taken along the line 12-12 of Figure 11.

Figure 13 is a cross section taken along the line 13-13 of Figure 11.

Figure 14 is a section taken along the line 14-14 of Figure 11.

Figure 15 is a plan view of the top of a modified form of my invention in which the middle rubber portion has a central flap on each side of which are laid stiffening members to be united to that flap.

Figure 16 is a section taken along the line 16-16 of Figure 15.

Figure 17 is a section taken along the line 17-17 of Figure 15.

Figure 18 is a section taken along the line 18-18 of Figure 15.

Figure 19 shows a modified form of my invention in which I provide a resilient insole and a binding about the periphery thereof of a relatively stiff material adapted to receive stitching.

Figure 20 is a section taken along the line 27-27 of Figure 19.

Figure 21 is a section taken along the line 28-28 of Figure 19.

Figure 22 is a section taken along the line 29-29 of Figure 19.

Figure 23 is a section taken along the line 30-30 of Figure 19.

Figure 24 shows in perspective the end, side and shank stiffening pieces shown in plan in Figures 7, 11 and 15. The recesses in the toe and shank portion are for the purpose of receiving corresponding projections in the middle rubber portion whereby firm and accurate engagement is provided.

Referring now more specifically to the drawings, in Figure 1 I show a shoe 1 having an outsole 2, a sock lining 3 and an insole 4 positioned therebetween. The insole 4 has perforations 5 which extend therethrough and perforations 6 in the sock lining match in position the perforations 5 in the insole. The insole 4 is formed of a peripheral portion of stiff material 7 such as leather or a composition of similar qualities adapted to retain the stitching therein. The central portion 8 of said insole is of resilient material such as expanded rubber, as for example closed cell rubber or sponge rubber, or any suitable corresponding resilient material. Located between the perforations 5 or adjacent thereto are grooves 9, the lateral or side walls of which are normally vertical and spaced one from the other. Accordingly the grooves shown are rectangular 70 in cross section.

At the bottom of the perforations 5 are bosses or extensions 10 which have a dual function. They increase the resilience of the construction and make for a softer step and at the same time facilitate the forced breathing action in

that the air forced from the compressed groove 9 can more easily escape into the perforation 5. That is the air can pass more readily by this relatively narrow end portion 10 of the perforation 5 than it could through the relatively wider area 5 from the groove to the perforation itself if a flat construction were used. Inasmuch as optimum resilience and breathing is here desired, all these features which tend to achieve that result are preeminently desirable.

As can be seen in Figure 3 these grooves are closed at each end and extend only part of the way across said resilient portion. Said grooves, therefore, constitute closed chambers having lateral walls which, in walking movement, move 15 away from one another causing expansion therefore drawing in air and, upon contraction, the walls move toward one another forcing out said contained air, which air then travels to and through the adjacent perforations to the foot as 20 shown more particularly in Figure 2.

The relative position and size of this groove is clearly shown in detail in Figures 5 and 6. In Figure 5 the groove is shown in normal position with its walls vertical and the groove of relatively less 25 cross sectional area. In Figure 6 the portion is shown when the foot is in bent position as in walking. There the groove is expanded by the general curving of the section and air is thereupon drawn into the groove cavity. As has been 30 stated, Figure 2 shows the downward movement of the foot with the corresponding compression of the grooves whereby the air is forced into and through means for permitting air to flow from below the insert to above the insole, e. g. perforations to the foot area. The perforations can be placed in any desired position so long as they afford communication between the grooves on the bottom of the insole and the shoe interior 35 above the insole.

Referring now again to Figure 1, the stitching 11 secures the leather edge member to the resilient material 8 through the flap 12. This flap construction is such as to provide a tapering away of the thickness of the insole at the edges thereof. Thus, the center portion of the insert 8 is thicker than the combined thickness of lap 12 and insole 1 (Figure 4) and a desirable ball cushion support for the foot is obtained. Another feature is the location of the stitching 11 50 immediately adjacent the point 13 where the main body of the resilient material contacts the leather edging. By positioning stitching at that point I provide against the separation of the resilient material from the leather edging and at 55 the same time provide greater flexibility for the assembly. This position immediately adjacent this point 13 is of particular importance because if the stitching were placed near the edge of the flap as it normally would be, there would be considerable separation and pulling between the various parts. Placed as it is, the stitching acts not only to connect the rubber insert to the leather edging, but it also secures the parts against any lateral displacement and further 60 holds the rubber flap extension down against the leather edge.

This construction is of further importance in that it prevents any separation of the parts at what is in Figure 5, the bottom joint of insert and 70 insole. If separation occurred here dirt or scraps might conceivably enter therebetween which might interfere with the proper resiliency of the insole. This is particularly applicable when the rubber flap extends across the bottom of the 75

leather instead of at the top, namely the reverse of what is shown in Figures 1 to 5.

At the rear of the resilient portion there extends the stiff material 16 of the shank of the insole which is, for example, leather or the like. The resilient material also extends toward the rear and is in the form of a thicker portion which forms a metatarsal support 17. The metatarsal also has perforations 18 therein for breathing purposes.

Referring now specifically to Figure 7 I show the shank portion of the insole 20 and the resilient forepart portion 21. The resilient portion has extending flaps 22 and 23. These flaps have 15 in the forepart and rear, extensions 25, 27 and 28 molded integrally therewith which are adapted to enter suitable recesses 29 and 30 in the toe stiffening piece 31 and the portion 20 respectively in order to secure a positive and accurate engagement therewith. The engagement is effected by inserting the toe piece 31 between the flaps in such a way that the projections 25 and 26 ride into the opening 29 in the indicated portion of the toe piece and similarly inserting the shank 25 portion 20 between the double flaps so that the projections 27 and 28 ride into and engage recess 30 in the shank portion.

The side stiffening members 33 and 34 are inserted between the flaps 22 and 23 at the sides 30 of the insole and then suitable rows of stitching 35 and 36 secure the respective stiffening members and shank portion to the resilient forepart portion. On the bottom of the resilient portion and shown in dotted lines are the grooves 31 35 which are adapted to be compressed to drive air through the perforations 38 which have the bosses 39.

As can be seen in Figure 10, the rear flap extension of the resilient portion is molded in the 40 form of a metatarsal support 40 which has suitable perforations 41 therein to provide for a greater flow of air and condensation of moisture.

Referring now to Figure 11 I show a modified form of my invention, wherein 50 refers to the shank of the insole and 51 to the resilient portion of my insole. The resilient portion is formed with an outwardly extending flap at the sides and front portion and a double flap at the rear by reason of the metatarsal support molded integrally therewith on the top. The resilient flap is indicated in the toe portion as 52, at the sides as 53 and the rear as 54. The added metatarsal support is 55.

As will be noted from the sections shown in 55 Figures 12, 13 and 14, the flap is only a portion of the thickness of the resilient main portion itself, the stiff leather portion 56 being of such thickness as to be flush with the top of the resilient insert. 56 is the toe stiffening portion, it being necessary to have a fairly stiff area at the toe section of the insole. This toe stiffening portion 56 and a recess 57 into which extends the projection 58 which is shown molded integrally with the flap 52. Side reinforcing members 60 60 and 61 similarly lie over the flap 53 and are secured thereto by stitching 62 and 63. It is to be noted that the line of stitching 63 is immediately adjacent the junction of the insert 51 and the stiffening member 60 so that there can be 65 no gap even under stress at that point. Such gapping would mean pinching of the sock lining with consequent wrinkling.

To effect the joining of the shank 50 to the resilient portion, I provide a projection 65 shown 75 molded integrally with the flap 54, which projec-

tion 65 fits into a recess 66 in the shank portion 50. As described hereinbefore, the resilient portion is provided with forced breathing grooves 68 and adjacent perforations 69 having bosses 70 at the bottom thereof.

Referring now to Figure 15, I show a still further modified form of my invention in which I provide a shank portion 75 and a resilient forepart portion 76 which has a single centrally extending flap 71. The toe stiffening portion 78 10 comprises an upper layer 79 and a bottom layer 80 of the shape shown at 78 which fit on each side of the centrally extending flap of the resilient portion and which layers have openings 81 and 82 into which projections 83 and 84 of 15 the centrally extending flap which are molded integrally with the flap, project. Similarly the side reinforcing members comprise an upper stiffening member 85 and a lower stiffening member 86 on each side of the centrally extending 20 flap 71.

To facilitate the joining of the resilient portion to the shank portion 75, I provide a centrally extending flap 88 having two side projections 89 which fit into corresponding openings 25 in the flaps 90 and 91 of the shank portion 75. Extending from the resilient portion is a metatarsal support 92. In the main part of the resilient portion are grooves 95 and adjacent thereto are perforations 96 having on the bottom thereof bosses 97.

My invention includes a size pad which may have on its lower surface the grooves which were described hereinbefore in connection with the resilient insole, and the size pad may also have 35 adjacent to these grooves, perforations, which perforations may or may not have at their lower termini, bosses. The grooves as described hereinbefore act to compress air and drive it through the perforations so that this size pad acts to 40 provide a forced breathing within the shoe by the alternate expansion and compression of the transverse grooves on the bottom of the size pad and the compression of air thereby. This size pad preferably has a feather edge about its periphery. It may or may not have integrally therewith metatarsal support. 45

Referring now to Figure 19 I show still another form of my invention in which the resilient portion 100 is bound around the edges with a stiff 50 material 101 which may be leather or any suitable stiff material of that nature. The resilient insole here is cut down at the edge as shown at 102 so that the binding 101 lies flush with the 55 resilient portion 100.

The shank portion 103 is joined to the resilient forepart by means of the fitting of the projection 104 of the resilient portion into the opening 105 in the shank portion and the stitching 106 and 107 secures said resilient portion to 60 said stiff shank portion. The stitching 110 secures the stiffening material 101 to the resilient portion 100 and here only a single row is required. This is a particularly effective method for providing a resilient forepart with the stiff edge 65 portion that is necessary for receiving and holding the stitching when the shoe is assembled. In the main portion of the resilient material are grooves 111 and adjacent perforations 112 having bosses 113 thereon. 70

Referring now generally to the constructions I have shown throughout these drawings, it is to be noted that it is desirable that the center part of the resilient forepart is of greater thickness than the peripheral portions thereof. This is to 75

provide a round bottom shoe effect and a center thickness for ball cushion support.

The flap extensions which extend over the stiffening portions are of special value not only because they provide a positive means for securing the insert to the insole, but also because they provide for a means for decreasing the thickness from the center to the periphery.

As can be noted, I have shown a number of 10 modifications of my invention whereby I can provide an insole with the resilient forepart portion and stiff toe, side and shank members in firm union therewith. The various forms of my invention which I have set forth provide for quick 15 assembly and this is especially an improvement over the form in which a leather insole has a cut out portion in the middle of the forepart thereof and an insert placed therein.

In Figure 24 I show in perspective the various 20 stiffening elements comprising the toe stiffening member 115 and the side stiffening members 116 and 117 and the shank portion 118. The particular way in which these stiffening members can be united to the resilient portion have been 25 set forth in detail in Figures 7 to 18.

Although I have shown the side stiffening members 116 and 117 separated from the shank portion 118, it is to be understood that they could be integral therewith, in which case the 30 resilient material is inserted therebetween and it merely remains for the toe stiffening portion 115 to be united with the resilient portion. Openings 119 and 120 in the toe stiffening member and shank portion respectively are for the 35 purpose of receiving suitable projections which may be molded into the resilient material so that a positive and accurate engagement is effected between the various parts.

Similarly I may provide means for engaging the 40 side stiffening elements with the resilient central forepart area. To do this, I may, for example, provide projections molded with the flaps of the resilient forepart area, which projections are adapted to engage corresponding recesses in the 45 side stiffening members. This provision for locking engagement between the various stiffening elements and the resilient material is of importance both because it provides speed of operation in assembly of the various parts, in that the operator can quickly insert a stiffening part, such as the toe stiffening member, and by fitting 50 the recesses therein with the projections on the resilient material, may determine the proper positioning of that toe stiffening element without delay.

Similarly with the side stiffening elements and the shank portion. In addition to accelerating the assembly operations, this construction also provides for more positive engagement of the 60 various units of my assembly so that before or after the stitching which permanently secures the various parts together, there can be no displacement of the parts with respect to one another. It is obvious that such a displacement 65 would be a serious matter in that it would cause interruption in the operations and produce rejects.

As can be seen, I have exemplified a number of 70 different constructions by means of which the periphery of the resilient forepart area of my insole may be so reinforced as to enable it to receive the necessary stitching. I have exemplified these particular constructions to exemplify my invention and do not wish to limit myself to the 75 particular constructions shown.

It will be noted that the metatarsal support which I provide is molded integrally with the resilient material and lies on a flap which rests on the stiff shank portion. This may be seen in Figures 10, 14 and 18 to 20, as well as the plan 5 views corresponding thereto.

In my construction, by providing the forced breathing over the entire forepart area of the foot as well as the "cookie" which is in the arch area, when such is employed, I provide a well 10 ventilated shoe that effectively and economically solves the problem of shoe ventilation. Specifically, the spaced transverse grooves provide a great bending flexibility for the insole because of the obvious physical advantages involved and the 15 bosses on the bottom of the perforations provide a spring effect which is of definite advantage for obtaining good walking properties. The perforations play their part in providing for greater 20 softness and compressibility for the resilient forepart itself.

Although I have exemplified a number of specific constructions it is understood that these constructions are by way of example of the principles of my invention only and that I intend to be 25 limited not by the specific constructions shown but only by the claims here appended.

I claim:

1. In combination, an insole, an opening in the forepart of said insole, an insert of rubber-like 30 material disposed in said opening, said insert having a relatively thick central portion and a relatively thin peripherally extending lap portion, said relatively thick central portion extending through said opening in said insole, said relatively thin peripherally extending lap portion being disposed over the portion of the insole adjacent to said opening, said extending lap portion being secured to said portion of the insole adjacent said opening, said central portion of said 40 insert being relatively thicker than the combined thickness of the insole and the peripherally extending lap portion to provide a ball cushion support, grooves located in said relatively thick central portion of said rubber insert, said grooves being substantially rectangular in cross-section, the walls of said rectangular grooves being spaced apart from one another, and means for permitting air to flow from below said insert to above said insole. 50

2. In combination, an insole, an opening in the forepart of said insole, an insert of rubber-like material disposed in said opening, said insert having a relatively thick central portion and a relatively thin peripherally extending lap portion, said relatively thick central portion extending through said opening in said insole, said relatively thin peripherally extending lap portion being disposed over the portion of the insole adjacent to said opening, said extending lap portion being secured to said portion of the insole adjacent said opening, said central portion of said insert being relatively thicker than the combined thickness of the insole and the peripherally extending lap portion to provide a ball cushion 65 support, grooves located in said relatively thick central portion of said rubber insert, said grooves having continuous side walls, the sidewalls of said grooves being spaced apart from one another, and means for permitting air to flow from below said 70 insert to above said insole. 60

3. In combination, an insole, an opening in the forepart of said insole, an insert of rubber-like material disposed in said opening, said insert having a relatively thick central portion and a 75

relatively thin peripherally extending lap portion, said relatively thick central portion extending through said opening in said insole, said relatively thin peripherally extending lap portion being disposed over the portion of the insole adjacent to said opening, said extending lap portion being secured to said portion of the insole adjacent said opening, said central portion of said insert being thicker than the combined thickness of the insole and the peripherally extending lap portion to provide a ball cushion support, grooves located in said relatively thick portion of said rubber insert, said grooves being substantially rectangular in cross section, the side walls of said rectangular grooves being spaced apart from one another, said grooves extending transversely across said relatively thick central portion, and perforations in said relatively thick central portion.

4. In combination, an insole, an opening in the forepart of said insole, an insert of rubber-like material disposed in said opening, said insert having a relatively thick central portion and a relatively thin peripherally extending lap portion, said relatively thick central portion extending through said opening in said insole, said relatively thin peripherally extending lap portion being disposed over the portion of the insole adjacent to said opening, said extending lap portion being secured to said portion of the insole adjacent said opening, grooves located in said relatively thick central portion of said insert, said grooves being substantially rectangular in cross section, the side walls of said rectangular grooves being continuous and spaced apart from one another, said grooves extending substantially transversely across said relatively thick central portion, the lateral walls of said grooves being adapted to move away from and toward each other during walking to pump air from said grooves, and perforations in said relatively thick central portion, said perforations being positioned to transmit air from said grooves to the interior of the shoe.

5. In combination, an insole, an opening in the forepart of said insole, an insert of rubber-like material disposed in said opening, said insert having a relatively thick central portion and a relatively thin peripherally extending lap portion, said relatively thick central portion extending through said opening in said insole, said relatively thin peripherally extending lap portion being disposed over the portion of the insole adjacent to said opening, said extending lap portion being secured to said portion of the insole adjacent said opening, said central portion of said insert being relatively thicker than the combined thicknesses of said insole and said peripherally extending lap portion and tapering down to provide a ball cushion support, grooves located in said relatively thick portion of said rubber insert, said grooves being substantially rectangular in cross section, the walls of said rectangular grooves being spaced apart from one another, said grooves extending substantially transversely across said relatively thick central portion, the walls of said grooves being adapted to move away from and toward each other during walking to pump air from said grooves, and perforations in said relatively thick central portion, said perforations being positioned to transmit air from said grooves to the interior of the shoe.

6. In combination, an insole, an opening in the forepart of said insole, an insert of rubber-like material disposed in said opening, said insert having a relatively thick central portion and a relatively thin peripherally extending lap portion, said relatively thick central portion extending through said opening in said insole, said relatively thin peripherally extending lap portion being disposed over the portion of the insole adjacent to said opening, said extending lap portion being secured to said portion of the insole adjacent said opening, said central portion of said insert being relatively thicker than the combined thickness of the insole and the peripherally extending lap portion to provide a ball cushion support, grooves located in said relatively thick central portion of said rubber insert, said grooves being substantially rectangular in cross section, the walls of said rectangular grooves being spaced apart from one another, the ends of said grooves being closed, and means for permitting air to flow from below said insert to above said insole.

7. In combination, an insole, an opening in the forepart of said insole, an insert of rubber-like material disposed in said opening, said insert having a relatively thick central portion and a relatively thin peripherally extending lap portion, said relatively thick central portion extending through said opening in said insole, said relatively thin peripherally extending lap portion being disposed over the portion of the insole adjacent to said opening, said extending lap portion being secured to said portion of the insole adjacent said opening, grooves located in said relatively thick central portion of said insert, said grooves being substantially rectangular in cross section, the side walls of said rectangular grooves being continuous and spaced apart from one another, said grooves extending substantially transversely across said relatively thick central portion, the ends of said grooves being closed, the lateral walls of said grooves being adapted to move away from and toward each other during walking to pump air from said grooves, and perforations in said relatively thick central portion, said perforations being positioned to transmit air from said grooves to the interior of the shoe.

8. In combination, an insole, an opening in the forepart of said insole, an insert of rubber-like material disposed in said opening, said insert having a relatively thick central portion and a relatively thin peripherally extending lap portion, said relatively thick central portion extending through said opening in said insole, said relatively thin peripherally extending lap portion being disposed over the portion of the insole adjacent to said opening, said extending lap portion being stitched to said portion of the insole adjacent said opening, said central portion of the said insert being relatively thicker than the combined thickness of the insole and the peripherally extending lap portion to provide a ball cushion support, grooves located on the bottom of said relatively thick central portion of said rubber insert, said grooves being substantially rectangular in cross section, the walls of said rectangular grooves being spaced apart from one another, and means for permitting air to flow from below said insert to above said insole.
